UNITED STATES PATENT OFFICE.

EDWARD W. SIBLEY, OF NEW HAVEN, CONNECTICUT, ASSIGNOR TO WINCHESTER REPEATING ARMS CO., OF NEW HAVEN, CONNECTICUT.

HAND-TRAP FOR CLAY PIGEONS.

1,306,393.

Specification of Letters Patent. Patented June 10, 1919.

Application filed April 3, 1919. Serial No. 287,308.

To all whom it may concern:

Be it known that I, EDWARD W. SIBLEY, a citizen of the United States, residing at New Haven, in the county of New Haven and State of Connecticut, have invented a new and useful Improvement in Hand-Traps for Clay Pigeons; and I do hereby declare the following, when taken in connection with the accompanying drawings and the characters of reference marked thereon, to be a full, clear, and exact description of the same, and which said drawings constitute part of this application, and represent, in—

Figure 1 a plan view of a hand trap constructed in accordance with my invention, showing two clay pigeons positioned therein preparatory to being thrown, and the handle being shown in its folded position by broken lines.

Fig. 2 an inside view of the trap with the handle broken away.

Fig. 3 an end view of the trap showing a clay pigeon therein in broken lines.

Fig. 4 a broken detail view in side elevation of the bent and threaded inner end of the handle shank with the locking-plate mounted thereupon.

Fig. 5 a face view thereof.

Fig. 6 a broken detail perspective view of the inner end of the bottom plate of the trap showing the shoulder formed therein and the locking-notch in the shoulder.

My invention relates to an improvement in hand traps for throwing clay pigeons of the type in which one or more clay pigeons are frictionally held in a combined trough-shaped carrier and guide having a handle arranged at an obtuse angle with respect to the longitudinal axis of the said carrier, the object of my present invention being to provide improved locking means for handles of hand-traps of the type described.

With these ends in view, my invention consists in a hand trap for throwing clay pigeons, having certain details of construction as will be hereinafter described and pointed out in the claims.

In carrying out my invention as herein shown, I employ a trough-shaped carrier and guide of sufficient length to hold and deliver two standard clay pigeons, being open at its outer end and narrower than half the diameter of such a pigeon. The said carrier comprises a bottom plate 2 upon which the clay pigeons 3 rest face down-

ward, as shown by broken lines in Fig. 1, and a top plate 4 yieldingly held in spaced relation to the bottom plate 2 from which it is normally separated by a space 5 (Fig. 3) a trifle narrower than the thickness of a pigeon so that when the same is inserted between the top and bottom plates it will be pinched between them with a sufficient grip to prevent it from accidentally falling out. As shown, the top plate 4 is formed with two parallel arms 6 arranged at a right angle to its longitudinal axis, located near its respective ends and having their ends bent to form knuckles 7 for the reception of a long pintle 8 passing through knuckles 9 formed by turning over the upper edge of the outer wall 10 of the trap, the said outer wall being made integral with the bottom plate 2 and turned upward at a right angle thereto from the rear edge thereof. Helical springs 11 encircling the pintle 8 have their respective ends engage with the outer face of the wall 10 and the upper face of the plate 4 so as to exert a constant effort to press the same downward toward the bottom plate 2, this downward movement being limited by stop arms 12 bent inward from the wall 10 at a substantial right angle thereto so as to overhang the bottom plate 2 as shown in Fig. 3. The construction above described, forms no part of my present invention, and may be replaced by any other construction designed to effect the same purpose. My particular invention resides in the provision of a device of the character described with a folding handle 13 formed with a rod-like shank 14 the end of which is bent at a right angle to form an arm or pivot-end 15 upon which a pear-shaped locking-plate 16 is fixed at a right angle thereto, the contracted end of this plate terminating in a straight sided locking-tongue 17 adapted to be entered into a locking-slot 18 formed to receive it in a transverse shoulder 19 produced by bending the inner end of the bottom plate 2. The projecting end of the arm or pivot end 15 is threaded as at 20 for the reception of a locking-nut 21 having a knurled edge and preferably corresponding in diameter to the main inner portion of the plate 16. The threaded end 20 of the arm 15 is passed through a hole 22 in the end of the plate 2 which turns upon the said end 20 as upon a pivot. When the hand trap is in use, the locking-tongue 17 is entered into the lock- 110

ing-slot 18 and held therein by the nut 21. A firm and strong coupling is thus established between the handle and carrier. To pack the article for transportation, the 5 nut 21 is unscrewed enough to permit the tongue 17 to be moved laterally out of the notch 18 after which the handle may be folded over into its closed position in the space 5 as shown by broken lines in Fig. 1.

10 I claim:—

15 1. In a hand trap for throwing clay pigeons, the combination with a combined carrier and guide adapted to receive and deliver a clay pigeon, of a pivotal handle having its shank bent to form a pivot-end which passes through said carrier, a locking-plate fixed upon the said pivot-end, and having a locking-tongue adapted to engage with the 20 said carrier for locking the handle in its open position with respect thereto, and a locking-nut mounted upon the said pivot-end for holding the said tongue in locking engagement with the said carrier.

25 2. In a hand trap for throwing clay pigeons, the combination with a combined carrier and guide adapted to receive and deliver a clay pigeon and having its inner 30 end formed with a shoulder containing a locking-slot, of a pivotal handle having its shank bent to form a pivot-end which passes through the inner end of the said carrier at a point adjacent to the said slotted

shoulder, a locking-plate fixed upon the said pivot-end at a right angle thereto and having a locking-tongue adapted to enter the 35 said slot for locking the said handle and carrier in the open position of the former, and a locking-nut mounted upon the said pivot-end for holding the said tongue in engagement with the said slot.

40 3. In a hand trap for throwing clay pigeons, the combination with a combined carrier and guide adapted to receive and deliver a clay pigeon and having the inner 45 end of its bottom plate formed with a transverse shoulder containing a locking-slot, of a pivotal handle having its shank bent to form a pivot-end which is threaded and which passes through the inner end of the carrier, a locking-plate fixed upon the said 50 pivot-end at a right angle thereto and having a locking-tongue adapted to enter the said slot in the shoulder of the said plate, and a locking-nut mounted upon the threaded end of the said pivot-end for holding the 55 said tongue in engagement with the said slot.

In testimony whereof, I have signed this specification in the presence of two subscribing witnesses:

EDWARD W. SIBLEY.
